UNITED STATES PATENT OFFICE.

MICHAEL LALLY, OF NORTH LAWRENCE, OHIO.

WRITER'S HAND-SUPPORT.

No. 839,159.

Specification of Letters Patent.

Patented Dec. 25, 1906.

Application filed May 31, 1905. Serial No. 263,142.

To all whom it may concern:

Be it known that I, MICHAEL LALLY, a citizen of the United States, residing at North Lawrence, in the county of Stark and State 5 of Ohio, have invented a new and useful Writer's Hand-Support, of which the following is a specification.

The invention relates to a ball-bearing writing-ring for supporting the hand of a writer.

The object of the present invention is to improve the construction of rings and to provide a simple and comparatively inexpensive one, designed particularly for the 15 use of penmen to render the hand firm and steady and lessen the labor of writing and adapted to prevent cramping the fingers.

A further object of the invention is to provide a ring of this character capable of ready 20 adjustment to fit any finger and adapted to enable the hand to move freely over the paper without soiling the same.

With these and other objects in view the invention consists in the construction and 25 novel combination and arrangement of parts hereinafter fully described, illustrated in the accompanying drawings, and pointed out in the claims hereto appended, it being understood that various changes in the form, proportion, size, and minor details of construction 30 within the scope of the claims may be resorted to without departing from the spirit or sacrificing any of the advantages of the invention.

5 In the drawings, Figure 1 is a perspective view of a ball-bearing writing-ring constructed in accordance with this invention. Fig. 2 is a sectional view of the same. Fig. 3 is a detail perspective view illustrating the 10 construction of the clip for securing the ring in its adjustment. Fig. 4 is a sectional view of the clip.

Like numerals of reference designate corresponding parts in all the figures of the 15 drawings.

I designates a ring having an enlarged portion 2 and consisting of a hoop or strip of metal provided with overlapped ends 3 and 4. The overlapped ends of the ring are 20 adapted to slide on each other for varying the size of the ring to enable the same to fit any finger, and after the ring has been properly adjusted to fit a finger it is secured in its adjustment by means of a clip 5. The clip 25 5 consists of oppositely-disposed combined guiding and clamping flanges formed inter-

gral with the end 4, which is arranged at the inner face of the end 3, and the said flanges extend outwardly and embrace the end 3, being terminated at or adjacent to the center 60 thereof, as clearly shown in Fig. 4 of the drawings. The flanges form the two sides of the clip, and when the latter is compressed against the end portion 3 the ring will be securely held in its adjustment. 65

The enlarged portion of the ring, which is substantially elliptical, as shown, is curved to conform to the curvature of the ring and forms a continuation of the adjacent portions of the ring and constitutes a portion of 70 the same, as clearly shown in Fig. 2 of the drawings. The outer face of the enlarged portion 2 of the ring is convexed and has mounted on it a plurality of bearings or settings 6, arranged in a cluster and consisting 75 of curved prongs and receiving a plurality of balls 7, which are preferably three in number, as shown in Fig. 1 of the drawings. These prongs, which are curved to conform to the configuration of the balls, extend beyond the 80 center of the same and embrace and retain the balls in the bearings. The balls extend from the curved portion 2 of the ring at different angles, and the outer supporting-surfaces are arranged in different planes, and 85 they form a tripod support for the hand. The balls are sufficiently loose in the bearings or settings to revolve freely when they are moved over a surface, and they enable the hand of the writer to move freely and frictionless, and thereby lessen the labor of 90 writing. The tripod support also permits the hand to have a free rocking or pivotal movement and does not require the hand to be maintained in a stiff or cramped condition. 95

The ring is designed to be worn on the little finger, and when it is desired to use the same for writing the enlarged portion is turned around to cause the balls to rest upon the paper or supporting surface, and they are adapted to prevent the hand from coming in contact with the paper and will avoid soiling the same. The ring is adapted to render the hand firm and steady, and it will 100 greatly facilitate rapid writing by preventing the hand from sticking or adhering to the paper, especially when the hand perspires. The ring also presents an ornamental appearance and may be worn at all times, so as 105 to be in position for instant use.

Having thus fully described my invention,

what I claim as new, and desire to secure by Letters Patent, is—

1. A writer's hand-support consisting of a ring of a size to fit the finger and provided with an enlarged portion curved to correspond to the curvature of the ring and constituting a portion of the same, and a cluster of antifriction devices arranged in the form of a setting and extending from the enlarged portion of the ring at different angles and having their outer supporting-faces arranged in different planes, said antifriction devices forming a tripod support for the hand and permitting a pivotal or rocking movement and a free sliding movement.
2. A writer's hand-support consisting of a ring provided with a cluster of antifriction devices arranged in the form of a setting and

adapted to rest upon the supporting-surface to enable the hand of a writer to move freely over the same, said ring being also provided with overlapping adjustable portions, and combined clamping and guiding flanges extending from opposite sides of one of the said portions and receiving and guiding the other, and adapted to be bent into frictional engagement with the same for clamping the ring in its adjustment.

In testimony that I claim the foregoing as my own I have hereto affixed my signature in the presence of two witnesses.

MICHAEL LALLY.
